5788X

L. YALE.
DRESSING STONE.

Patented Jan. 20, 1830.

Jan 10 1850 109

Lyons' Patent Office, U. S. A.

Letters Patent. No. 5788

The Schedule referred to in these Letters Patent, and making part of the same, containing a description in the words of the said Lyons' full history of his improvement for hewing, picking and milling stone by means of steel picks, wheels and hammer attached to a common handle &c.

A represents the end view of a shaft from 9 to 12 inches in diameter according to the size of the machine - length & according to M^o of handles used b. c. d. e. represent cases or caps framed into the shaft, C represents a lever or handle to which the chisel or picks or hammer (1.2.3) are fastened by screws. C represents the end view of a piece of timber framed at each end into the sides of the machine permanently on which the lever or handle, levers or handles used in the machine rest, and which when the cog C depresses that end of the lever or handle & raises the other end receives the descending lever & prevents the chisel or picks (which by means of screws are of equal length at equal distances from the ends of the levers or handles) from operating at unequal depths upon the stone.

The lever or handle is hung near the middle by a bolt or rod passing thro' near the top of the post D & its opposite in the machine. The motion to be given to the shaft A (if used by hand power) is by a common crank, the perpendicular cog wheel attached to the end of the shaft A - being of a horizontal cog wheel, situated above or below the shaft A, & being turned by means of horse power, & connected to the shaft A by a small spring made of

wood, wire or steel as may be necessary fastened either upon or near the shaft passing from the foot of the post D to its opposite in the machine, and the upper end projects upon the lever or handle so as to keep it in a position horizontal to the centre of the shaft. Now Remarks. By inspection of this draft it is obvious 1st. that this machine may be constructed so as to contain from one to fifty levers or handles with from one to three chisel or picks on the end of each (as 1.2.3.) that the shaft A must contain as many rows of eyes as there are levers or handles B that each lever or handle requires at least one spring and that guides or upright pieces of timber are framed between the levers or handles C so as to give direction to the descending chisel or picks.

3rd. That supposing the shaft to contain 16 eyes to each lever or handle that the machine has 16 levers or handles, 3 chisels on the end of each one revolution of the shaft will occasion 216 strokes with a chisel upon the stone with the force of which the spring is capable. That should the shaft A revolve 30 times in a minute the stone will have received in that time 6480 strokes.

4. That a carriage or carriages are to be constructed containing no new principle in mechanics, calculated to facilitate the operations of the machine in the having, dressing & drilling of stone & that it is the object of the petitioner to secure to himself the right of building, using and vending any carriage or carriages for that purpose, leaving all others the right of building like carriages if they please for different uses & purposes.

5. That the main object of the petitioner is to prohibit all persons without his consent, with the intent to deprive him of his having, picking or drilling of stone by means of steel picks chisel or hammers, although

To any lever or lever, handle or handles, sustained
as aforesaid by springs made of wood, wire or in
steel wire, propelled by means of a staff set in
motion by hand, horse, water or steam power.
